UNITED STATES PATENT OFFICE.

JOHN L. GIVEN, OF BRIDGEPORT, CONNECTICUT.

PNEUMATIC CASH-CARRIER APPARATUS.

SPECIFICATION forming part of Letters Patent No. 411,334, dated September 17, 1889.

Application filed May 9, 1889. Serial No. 310,118. (No model.)

To all whom it may concern:

Be it known that I, JOHN L. GIVEN, of Bridgeport, in the county of Fairfield and State of Connecticut, have invented certain 5 new and useful Improvements in Pneumatic Cash-Carrier Apparatus, of which the following is a full, clear, and exact description.

This invention consists of the combination, with a pneumatic tube for the transmission 10 of a carrier or other article therethrough, of certain construction and arrangement of parts at the delivery end of such pneumatic tube, so that the carrier or other article transmitted through the tube will be automatically delivered therefrom at such delivery end and with comparatively little force, all substantially as hereinafter fully described, reference being had to the accompanying sheets of drawings, in which—

20 Figure 1 represents the present invention in front view; Fig. 2, a side elevation; Fig. 3, a side elevation showing change of position of one of the parts; Figs. 4 and 5, longitudinal central sections on line 4 4, Fig. 1, showing the 25 operating parts in two different positions, to be hereinafter referred to; Fig. 6, a detail longitudinal central section on line 6 6, Fig. 2; Fig. 7, a cross-section on line 7 7, Fig. 6; and Fig. 8, a cross-section, enlarged, on line 8 8, Fig. 5. Fig. 9 is a detail side view of some of 30 the parts, Figs. 4, 5, 6, 7, and 8 being enlarged. Fig. 10 is a detail sectional view to be hereinafter referred to. Fig. 11 is a longitudinal section on line 6 6, Fig. 2, to be 35 hereinafter referred to.

In the drawings, A represents the end of a pneumatic tube for the transmission of a carrier or other article therethrough, and secured by a screw-thread in the lower end of a 40 standard B, secured in any suitable manner to the table or stand C. This standard B is in tube form and makes practically a continuation of the pneumatic or main tube A, and has an opening D in the front for the delivery 45 of the carrier or other article thereat, and to facilitate such delivery the standard is secured in an inclined or angular position to the table, with its delivery-opening on its under or front side, as shown in the drawings.

50 The upper end of the standard has a cap E, which screws onto a sleeve or coupling F, which sleeve in turn screws into the upper

end of the standard, as shown in section in Figs. 4, 5, and 6 more particularly. This cap surrounds the upper part of the sleeve, leaving a chamber G around and above it, as shown. Screwing into the side of this cap E at a is an elbow H, having the end of a pneumatic tube J secured thereto by a screw-thread, all as shown more particularly in Fig. 6.

The tube A is the portion of the main tube for the delivery of the carrier or other article at the station where the standard is, and the tube J is the portion of the main tube making the return-tube for the sending of a carrier 65 or other article therethrough from the station where the standard is placed back to the station from which it came, or for communication with the air-exhaust apparatus for the proper exhaustion of air in the tube for the 70 transmission of the carrier or other article; but when used as a tube by which to return or to send a carrier therethrough it is provided with an opening K, arranged to be covered with a gate or valve L, pivoted at b 75 thereto. This return-tube can be inclined in the same direction as the standard, as shown in Figs. 1 and 2, or it can be in a vertical position, as shown in Fig. 3, the working of this return-tube not requiring any special angle 80 of inclination.

M is a short tube within the standard, open from end to end, its exterior diameter somewhat less than the internal diameter of the standard to leave a space d around the same 85 between it and the standard, and having on each end an enlarged portion or flange N, each of which flanges closely fits the internal diameter of the standard sufficient to practically prevent air from passing between the 90 two, and yet loosely enough for the tube M to slide freely up and down within the standard. When this sliding tube M is down in its normal position, closing the delivery-opening, it rests upon the upper end of the pneumatic 95 tube A, as shown in Fig. 4 in cross-section, and in such position its two flanges cover the lower end e and the upper end f of the delivery-opening D to practically close air-communication with the pneumatic tube at the 100 delivery-opening.

The internal diameter of the sleeve F is the same as that of the standard and coincident therewith. Its upper end g is solid; but just

below this end large openings P are made in its side, as shown in cross-section, Fig. 7, (in the present instance four in number,) making free communication for air between the interior 5 of the sleeve and standard and the chamber G, made by the cap around and above the sleeve, which chamber has free communication with the return-tube J by a passage h in the side leading from said chamber to said 10 return-tube, as shown in cross-section in Fig. 6, so that when the sliding tube M is in its normal position, as shown in Fig. 4, air can pass then through the sliding tube M up and out at the sleeve-openings P into the cap-chamber G, and into the return-tube to the air-exhausting apparatus; but when the sliding tube is moved up into the position shown in Fig. 5, abutting against the upper closed end g of the sleeve, its upper end flange will then 15 be above the bottom of the sleeve-openings, leaving a portion of each open and free for air to pass through, and its lower end flange below the upper end f of the delivery-opening D, so that air can then freely pass in at 20 the delivery-opening at m (see Fig. 5) between the sliding tube and the standard and out at the sleeve-openings into the cap-chamber, and thence to the return-tube to air-exhaust. 25

30 The sliding tube and its operation in relation to the delivery-opening and the carrier are substantially the same as described and shown in Letters Patent of the United States issued to me dated March 20, 1888, and numbered 379,890, and needing no particular description herein; but the operation of the present sliding tube in connection with the other parts of this invention is as follows: The standard is placed at the station where 35 it is desired to deliver the carrier or other article and in the inclined position shown, and the pneumatic tubes for the transmission of the carrier therethrough are properly connected therewith and the air-exhaust apparatus for the exhaustion of air in the direction of the arrows, Figs. 4, 5, and 6 more particularly, and as a carrier Q coming along the tube A, from the effect of exhausting air in front of it, reaches and makes a union with 40 the open lower end of the sliding tube M, as shown in Fig. 4, it closes such opening to the passage of air therethrough, when the sliding tube then moves with the carrier upward until it strikes against the sleeve-head g, closing 45 the upper end of the sliding tube to the passage of air through it, so that air then freely passes in at the delivery-opening D and between the standard and tube and out at the sleeve-openings into the chamber G, and thence 50 to the return-tube, and to the air-exhaust apparatus, consequently relieving the pressure of air upon the carrier, which releases its hold with the sliding tube, from which it drops and falls out of the standard onto the 55 table in front, on account of the inclined position of the standard, for the attendant to open it and remove its contents, and, if need

be, return it to the station from which it came. Immediately the carrier is released from the lower end of the sliding tube air 70 can then freely pass through it, which, relieving the air-pressure on it, falls by its gravity to its seat, closing the delivery-opening to the entrance of air thereto, and leaving the pneumatic tube and its connecting 75 parts in condition for the exhaustion of air therefrom, for the transmission through the tube to the delivery-opening of another carrier or other article or of the return of the same by the return-tube. The return of the 80 carrier is accomplished by opening the valve or gate of the return-tube and placing it in the opening leading thereto, its pointed end n down, and then, closing the valve, it is transmitted along the return-tube to the station 85 from which it came by the air-exhausting apparatus.

In the manufacture of the apparatus it is preferable to make the standard of cast-iron, the pneumatic tubes being made of metal in 90 the usual way of making tubes, and in lieu of having the sleeve it can be dispensed with and the cap be secured to the standard directly over its upper end, which can be closed in any suitable manner, and have the side 95 openings P, for the operation, as before, and substantially as shown in detail in cross-section in Fig. 10, in which the standard-tube has its upper end at r closed and the openings P in its side and opening into the chamber G, 100 formed by the cap E, secured over the end to the outside of the standard by a screw-thread, as shown in said figure.

The space or chamber R above the side 105 openings P in the tube or standard, as shown more particularly in Fig. 11, confines the air 110 therein, so that when the upper end of the sliding tube, with the carrier in union with its lower end, has passed above the side openings P the air in such chamber R and in the 115 sliding tube will be more or less compressed and make a cushion for the sliding tube and carrier, causing a resistance to the movements of the same and aiding somewhat in releasing the carrier from its union with the sliding tube for its discharge at the delivery-opening, so that with the entrance of air at the delivery-opening the carrier will be practically relieved of momentum and be delivered with a slight degree of force. 120

To prevent wear as the sliding tube strikes the head of the sleeve or the upper end of the tube A, the inner side of the sleeve-head has secured to it a piece t of soft yielding material—such as leather—and the upper end of the tube A has a piece u of similar material. 125

The standard is inclined, so that the carrier, after being relieved of its hold upon the sliding tube, will, as it drops therefrom by its gravity, fall out of the standard onto the table, while the incline of the standard for such purpose is not so much but that the sliding tube, after the carrier has ceased its connection therewith, will by its gravity return to its 130

normal position and close the delivery-opening. Such incline, it is preferable, should be about sixty degrees, although it can be of any angle that will accomplish the result desired.

5 It can also incline sidewise or in any direction.

Having thus described my invention, what I claim is—

1. The combination, with a pneumatic tube 10 for the transmission of a carrier therethrough, provided with an opening for the delivery thereat of the carrier, having its end closed and provided with side openings, leaving a space or chamber in said tube between the 15 closed end and side openings, of a chamber surrounding the end of said pneumatic tube, having communication therewith through the side openings, and with a tube leading therefrom to the air-exhaust apparatus, for the 20 purpose specified.

2. The combination, with a pneumatic tube 25 for the transmission of a carrier therethrough, provided with an opening for the delivery thereat of the carrier, and a sliding tube arranged to move back and forth within said tube to open and close said opening and open from 30 end to end and adapted to receive the carrier to close the opening through said tube, of a chamber surrounding the end of said pneumatic tube and having communication with the pneumatic tube and a tube leading therefrom to the air-exhaust apparatus.

3. The combination, with a pneumatic tube 35 for the transmission of a carrier therethrough,

provided with an opening for the delivery 35 thereat of the carrier, and a sliding tube arranged to move back and forth in said tube to open and close said opening, open from end to end and adapted to receive the carrier to close the opening through said tube, 40 said pneumatic tube having a thimble or sleeve secured to its end, having a closed end and side openings P, of a cap E, secured over said sleeve to said tube, forming a chamber having communication with the tube A 45 through said sleeve, and a tube J, leading therefrom to the air-exhaust apparatus, for the purpose specified.

4. The combination, with a pneumatic tube 50 for the transmission of a carrier therethrough, provided with an opening for the delivery thereat of the carrier and an opening or openings at its upper end communicating with a chamber communicating with the air-exhaust apparatus, of a sliding tube within the pneumatic tube of less diameter than the pneumatic tube and having its ends enlarged to fit the pneumatic tube and arranged to slide back and forth therein to open and close said delivery-opening, for the purpose specified. 55 60

In testimony whereof I have hereunto set my hand in the presence of two subscribing witnesses.
